UNITED STATES PATENT OFFICE.

MELVILLE CLARK, OF CHICAGO, ILLINOIS.

Solo-Playing Automatic Piano.

1,024,677.

Specification of Letters Patent. Patented Apr. 30, 1912.

Application filed May 17, 1911. Serial No. 627,749.

To all whom it may concern:

Be it known that I, MELVILLE CLARK, a citizen of the United States, residing at Chicago, in the county of Cook and State 5 of Illinois, have invented new and useful Improvements in Solo-Playing Automatic Pianos, of which the following is a specification, reference being had to the drawings forming a part thereof.

10 The purpose of this invention is to provide an improved construction of a pneumatic player action for pianos and like instruments, which is intended for reproducing music of two parts, as for instance, 15 melody and accompaniment.

It consists of the features and elements described and shown in the drawings as indicated in the claims.

In the drawings: Figure 1 is a fore and 20 aft vertical section of a player action mounted within the casing of a piano. Fig. 2 is a front elevation of a tracker board. Fig. 3 is a rear elevation of the tracker board and primary pneumatics with 25 their connecting tubes. Fig. 4 is a detail section of a modified form of the parts shown in Fig. 1.

The drawings illustrate this device largely in a conventional manner since the 30 present invention relates rather to a few details of construction and arrangement than to the action as a whole.

Briefly, the mechanism comprises a set 35 of motor pneumatics designed to operate upon the respective keys of the instrument. It is contemplated that there shall be available from two separate sources, comparatively rarefied air, one source supplying the air at a greater degree of rarefaction than 40 the other, and the purpose of the devices hereinafter described being to supply the motor pneumatics with this more rarefied air when melody notes are to be played, or to supply these same motor pneumatics 45 with air, that is less rarefied, for playing the notes of an accompaniment to said melody.

Referring to Fig. 1,—A, is the key bed 50 and B, is a key of a piano action, the remainder of which is diagrammatically indicated at, C. Mounted above the keys there is shown a set of motor pneumatics, D, arranged as usual in several banks, of 55 which the respective pneumatics are laterally staggered or overlapped with respect to one another, so as to permit them to be

of greater width than the piano keys and still to be so positioned that their key actuating pitmen, E, may register with the respective keys of the key board. There is one 60 motor pneumatic provided for each key of the key board or for each key within a given range which it is desired to operate and control automatically by means of the pneumatic action. At, F, there is shown the 65 tracker board, and at, G, there is indicated the usual perforated controller sheet carried upon the rolls, J¹ and J², by which it is fed across the mouths, F¹, of the tracker ducts. These ducts run back through the 70 tracker board, emerging in two rows, staggered with respect to each other where they are provided with nipples for connection with the rubber tubes which run to the two primary pneumatic actions, H and L, respectively, hereinafter described. As is usual, each of these primary actions is contained in a closed chamber in which there is maintained a partial vacuum. In the present construction, the condition of the 75 chamber, H¹, may be considered as being that of a higher vacuum than the chamber, L¹. Such relative vacuums are maintained by means of any desired form of pumpers and reservoirs not shown, but which may communicate with the chambers through the trunk pipes, M and N, and their connecting ducts, M¹ and N¹, entering the chambers at, M² and N², respectively. The 80 chambers, H² and L², communicate with the motor pneumatics through two series of ducts, H² and L², respectively. Nearly every motor pneumatic is connected through these ducts with both vacuum chambers; but since it is not necessary that the range 85 of the accompaniment run quite so high on the key board as that of the melody action, and since the accompaniment usually ranges somewhat lower on the key board than the melody, the two primary actions do not perfectly overlap; and the high tension action being a part of the melody-producing mechanism, extends beyond the low vacuum primary chamber at the treble end of the piano, while the reverse is true at the bass end, as is indicated in Fig. 3. Each of the 90 ducts, H², communicates directly with the chamber, L¹, through an aperture, L², which is provided with a valve, L³. This valve is 95 operatively connected with the moving wall of a primary pneumatic bellows, L⁴, which 100 communicates through a tube, L⁵, with a 105 110

duct of the tracker board. The duct, L^2 , is also provided with a second aperture, L^6 , through which under certain conditions it may communicate with the outer air, that is, through which atmospheric pressure may be admitted to the duct. When a perforation of the controller sheet registers with the mouth, F^1 , of one of the ducts, F^x , of the tracker board, atmospheric pressure is admitted through the tube, L^x , to the interior of the pneumatic, L^5 ; since this pneumatic is contained in a chamber which is under a pressure lower than atmospheric, the result is that the pneumatic, L^5 , is expanded and unseats the valve, L^4 , from the aperture, L^2 , moving it to a position covering the aperture, L^6 . The exhaust of the chamber, L^1 , is thus admitted to the duct, L^2 , and thence into the corresponding motor pneumatic, D , with which it communicates. This rarefaction of the air within the bellows, L^5 , which is exteriorly subject to atmospheric pressure, causes it to collapse and to actuate its key striker, D^1 , thus sounding the desired note.

As thus far described, the construction and mode of operation are that of a usual and well known type of pneumatic player action.

The above description applies equally well to the arrangement of the high tension action, H , and its connections which are shown in Fig. 1, with reference numerals corresponding to those of the low tension action, L . The tubes, H^x , are shown leading to certain ducts of the tracker board, F . Fig. 3 indicating that the end portions of the tracker board in this case are taken up with the ducts corresponding to this high vacuum action, while the middle part is connected with the primary pneumatics of the low tension action, L .

By reference to Fig. 1, it may be noted that both of the ducts, L^2 and H^2 , connect with a single duct, D^2 , leading to the motor pneumatic, D . With no more parts than have already been described, it will be seen that both of the ducts, L^2 and H^2 , would normally be open to the atmosphere through their respective apertures, L^6 and H^6 , and that though the operation of primary, L^5 , for example, would move the valve, L^4 , to close the aperture, L^6 , the aperture, H^6 , would still remain open and the partial vacuum of the chamber, L^1 , would be relieved therethrough, instead of operating the motor pneumatic, D , as intended. Proper operation on the high vacuum side would be similarly defeated through the aperture, L^6 , which would normally remain open in spite of the closing of the aperture, H^6 . To overcome this difficulty, there is provided what may be termed a floating valve, L^7 , carried between springs, L^8 , on an extended portion of the pitman, L^9 , which carries the valve, L^4 , in normal posi-

tion; as indicated in Fig. 1, this valve is seated over the aperture, L^6 , serving to keep it closed to permit proper operation of the motor pneumatic when such operation is initiated through the high tension action, H . In case the low vacuum action is brought into service, the valve, L^7 , is carried with the valve, L^4 , and seated over the aperture, H^6 , while the valve, L^4 , closes the aperture, L^6 , thus completely excluding atmospheric pressure from the passages, L^2 and H^2 , and insuring actuation of the motor pneumatic, D .

Due to the difference in the two partial vacuums in the chambers, L^1 and H^1 , respectively, there arises another difficulty in consequence of the fact that both ducts, L^2 and H^2 , connect with a common duct, D^2 . When a primary pneumatic of the action, H , is in service, having opened its valve, H^4 , the higher vacuum will be operative through the duct, H^2 , as well as through the duct, L^2 , unless there is some provision for preventing it. In that case, the pressure on the valve, L^4 , would be greater on the side facing the chamber, L^1 , than on the side which stands in the duct, L^2 , so that the greater pressure from within would tend to unseat the valve, L^4 , and relieve the higher vacuum of the chamber, H^1 , rendering it no more effective for actuating the motor pneumatic than the lower vacuum of the chamber, L^1 , would be. To prevent this undesired result, there is placed in the passage, L^2 , near its junction with the duct, D^2 , a flap valve, L^{10} . Since the pressure in the passage, L^2 , would always be greater than that resulting from the partial vacuum of the chamber, H^1 , and the latter when communicated through the duct, D^2 , will operate to cause the valve, L^{10} , to seat, and thus automatically cut off communication with the low vacuum action and its passages. In connection with this last described valve, L^{10} , it may be noted that it incidentally accomplishes also the function of the supplemental valve, L^7 , as far as it relates to the aperture, L^6 , since it effectively cuts off all connection of this aperture with the duct, H^2 , when the latter is in service. This observation suggests a modified form of supplemental valve to replace the valve, L^7 , and such modification is illustrated in Fig. 4. It consists of a supplemental primary pneumatic, L^{11} , mounted exteriorly on the chamber, L^1 , to communicate therewith through a port, L^{12} , so as to be normally collapsed under the influence of the partial vacuum in the chamber, L^1 . A duct, L^{13} , branching from the duct which leads into the primary pneumatic, L^6 , furnishes atmospheric pressure from the tracker board to the pneumatic, L^{11} , whenever such pressure is similarly furnished to the pneumatic, L^6 , so that the two will be simultaneously expanded. The movable wall of the pneu-

matic, L^{11} , carries a supplemental valve, L^{70} , which as above pointed out, is needed only in connection with the aperture, H^6 , during operation of the low vacuum primary, L^5 , by the simultaneous expansion of the primaries, L^5 and L^{11} , the valves, L^4 and L^{70} , are properly seated over the apertures, L^6 and H^6 , respectively, and thus the partial vacuum of the chamber, L^1 , is communicated to the motor pneumatic through the ducts, L^2 and D^2 , without danger of being relieved.

It will be understood that the perforated note sheet, which is intended to control the operation of this action, will have perforations cut throughout the middle portion of its length corresponding to the notes of the accompaniment, so as to register with the ducts, F^1 ; while the perforations corresponding to the notes of the melody will be disposed in the marginal portions of the sheet, so as to register with the ducts, F^h . In the case of music of the class which may be termed purely instrumental, and in which it is not particularly desired to accentuate the theme, the perforations would be confined to the middle portion of the sheet, so as to register only with the ducts, F^1 , the ducts, F^h , remaining covered by the unperforated margins of the sheet, so that the high vacuum or melody action would not be brought into service.

I claim:

1. In an automatic musical instrument, in combination with a key striker and a motor pneumatic operatively connected therewith, a duct leading from said motor pneumatic and having two branches, each branch being provided with two apertures, one of said apertures in each branch being positioned to communicate with the atmosphere at normal pressure, the other apertures communicating with separate sources of air at different pressures, respectively, other than normal pressure, a valve in each branch adapted for closing alternately the two apertures thereof, a primary pneumatic operatively connected with each of said valves, a supplemental valve adapted for closing the normal pressure aperture of one of the branch ducts, means for moving said valve simultaneously with the valve of the other branch duct, a tracker board provided with a duct corresponding to each of the primary pneumatics, and means connecting the latter with their respective ducts.

2. In an automatic musical instrument, in

combination with a key striker and a motor pneumatic operatively connected therewith, a duct leading from said motor pneumatic and having two branches, each branch being provided with two apertures, one of said apertures in each branch being positioned to admit atmosphere at normal pressure, the other apertures connecting, one with a low vacuum and the other with a source of higher vacuum, a valve for each branch adapted for closing alternately the two apertures thereof, a primary pneumatic operatively connected with each of said valves, a supplemental valve adapted for closing the normal pressure aperture of one of the branch ducts; means for moving said valve simultaneously with the valve of the other branch duct, a check valve in the duct communicating with the low vacuum, a tracker board provided with a duct corresponding to each of the primary pneumatics, and means connecting the latter with their respective ducts.

3. In an automatic musical instrument, in combination with a key striker and a motor pneumatic operatively connected therewith, a duct leading from said motor pneumatic and having two branches, each branch being provided with two apertures, one of said apertures in each branch being positioned to admit atmosphere at normal pressure, the other apertures connecting, one with a low vacuum and the other with a higher vacuum, a valve for each branch adapted for closing alternately the two apertures thereof, a primary pneumatic operatively connected with each of said valves, a supplemental primary pneumatic, a leak port connecting the same with one of said vacuums, a duct connecting the supplemental primary with the primary which operates the valve controlling said vacuum, a valve carried by the movable wall of the supplemental primary, in position for closing the normal pressure aperture of the duct which connects with the other vacuum, a tracker board provided with a duct corresponding to each of the first two primary pneumatics, and means connecting the latter with their respective ducts.

In testimony whereof I have hereunto set my hand at Chicago, Illinois, this 15th day of May, 1911.

MELVILLE CLARK.
